IMPLEMENT FOR ATTACHING ORNAMENTAL JEWELS TO FABRIC

Nathan K. Morris, Avon, N. J.

Application March 30, 1954, Serial No. 29,774

Term of patent 7 years

(Cl. D54—13)

To all whom it may concern:

Be it known that I, Nathan K. Morris, a citizen of the United States of America, residing at city of Avon, county of Monmouth, and State of New Jersey, have invented a new, original, and ornamental Design for an Implement for Attaching Ornamental Jewels to Fabric, of which the following is a specification, reference being had to the accompanying drawing forming a part thereof.

Figure 1 is a perspective view of an implement for attaching ornamental jewels to fabric, embodying my new design;

Figure 2 is a side elevation thereof; and

Figure 3 is a top plan view of the same.

I claim:

The ornamental design for an implement for attaching ornamental jewels to fabric, as shown.
